UNITED STATES PATENT OFFICE.

EDGAR A. RUSSELL, OF NEW HAVEN, CONNECTICUT, ASSIGNOR TO
JUDSON B. UNDERWOOD, OF NEW HAVEN, CONNECTICUT.

SHADE-HOLDER.

SPECIFICATION forming part of Letters Patent No. 767,313, dated August 9, 1904.

Application filed February 9, 1903. Serial No. 142,460. (No model.)

To all whom it may concern:

Be it known that I, EDGAR A. RUSSELL, a citizen of the United States, residing at New Haven, in the county of New Haven and State 5 of Connecticut, have invented certain new and useful Improvements in Shade-Holders, of which the following is a specification, reference being had therein to the accompanying drawing.

- 10 My invention relates to improvements in shade-holders, its object being, among other things, to provide a one-piece shade-holder that can be economically constructed and readily attached and detached.
- 15 To these and other ends my invention consists in the shade-holder constructed substantially as hereinafter described, and more particularly pointed out in the claims.

Referring to the drawing, which is a side 20 elevation, partly in section, of my new and improved shade-holder, I have illustrated the same as being attached to the socket of an ordinary incandescent lamp.

This shade-holder is preferably made from 25 sheet metal and provided with a socket-collar 1, having threads thereon which engage the threads upon the shank 2 of the lamp-socket 3, and a threaded shade-collar 5, connected with the collar 1 by a flaring flange 4. The 30 flange 4 can be either solid or perforated by apertures 6 of any desired form. Within the interior of the collar 5 is threaded the head 7 of the shade 8.

In my improved shade-holder there is but 35 one piece, the use of all additional parts being dispensed with, and the threaded engagement of the holder with the lamp-socket and the shade with the holder provide a quick and convenient means of attaching and detaching 40 them.

By the use of a spun thread, as shown, the collar can be threaded into or onto the lamp socket and shade.

I do not desire to be limited to the particular form of shade-holder shown, as the variety 45 of forms in which my invention can be made is almost endless, and I would therefore have it understood that I do not limit myself to the exact construction herein shown.

What I claim as new, and desire to secure 50 by Letters Patent, is—

1. A shade-holder constructed of a single piece of metal of uniform thickness throughout and having two coaxial annular collars of different diameters and located one above the other, with a downwardly-flaring flange connecting the bottom of the upper collar with the top of the lower collar, each of said collars having a spun thread thereon, whereby it may be secured internally or externally, 55 substantially as shown and described.

2. A shade-holder constructed of a single piece of sheet metal of uniform thickness throughout, and terminating at each end in a collar, having an inwardly and outwardly projecting thread, whereby the collars may be secured internally or externally, each of said collars being of different diameters, coaxial 65 with each other, and joined by a circular flange connecting the inner ends thereof, substantially as shown and described.

3. The combination with a lamp-socket; of a shade-holder constructed of a single piece of sheet metal of uniform thickness throughout, said shade-holder being constructed with an 75 internally and externally threaded annular collar upon each end thereof; and a flange connecting the inner ends of said collars, substantially as shown and described.

In testimony whereof I affix my signature in 80 presence of two witnesses.

EDGAR A. RUSSELL.
